UNITED STATES PATENT OFFICE

AUGUST RAPP, OF ISERLOHN (WESTFALEN), GERMANY

HOLDER WITH PULLEY FOR DRAWING CURTAINS

Application filed January 2, 1931, Serial No. 506,221, and in Germany January 3, 1930.

The present invention relates to a holder and pulley or roller for drawing curtains, which are supported by a hollow bar having a slit on its under side. Holders are known in which the pulley is arranged in a cap supporting a hook. The essence of the present invention is comprised in the fact that the cap is provided with angular recesses embracing lateral trunnions of the pulley.

10 The invention offers the advantage of providing a bearing for the pulley wheel axle which operates practically without friction losses, this being brought about by the simplest means. In addition to this, a firm support of the pulley inside the holder is assured.

Forms of execution of the subject matter of the present invention are shown by way of example of the appended drawings.

20 Fig. 1 being a side elevation of one form of construction, and

Fig. 2 a vertical section along the broken line A—B.

Fig. 3 shows a side elevation of the holder 25 after the cap and the pulley wheel have been removed.

Fig. 4—6 are side elevations of three further forms of construction of the holder.

In the form of construction shown in Figs. 30 1 to 3 the sheet metal holder *a* is fitted at its lower extremity with a hook *b*, whilst the upper portion is provided with an opening *c*. The pulley *d* runs inside this opening. In order to avoid unnecessary friction, the opening *c* must be of a larger diameter than the outer diameter of the pulley *d*.

35 Joined to the holder *a* is a cap *e* which covers the upper portion of the pulley. The joint can be effected in any desired way. In 40 the form of construction as shown by way of example, the cap is on its upper side provided with an aperture through which protrudes a tongue *f* of the holder *a* which is bent down after the cap has been slipped on.

45 At its lower edge and on either side the cap is provided with a recess *g* which serves the purpose of providing a bearing for the axle *h* of the pulley *d*. The axle and pulley are preferably made in one piece.

50 With reference to Fig. 1, the notch or re-

cess *g* is of an angular shape. A semi-circular form would also be possible. The angular shape has the advantage of reducing the friction between the axle of the pulley and the cap. The cap prevents the pulley from 55 falling sideways out of the holder; on the other hand, the pulley is free to run practically without friction, owing to the fact that the pulley does not contact with the cap except at its axle.

With reference to the form of construction shown in Fig. 4, the holder *i* is made of wire. The wire is bent over at *k*, thus forming a double wire. One end of this double wire forms a hook *l*, whilst the other end of the 65 double wire is bent into the shape of a ring *m*. Pressed on to the upper portion of the ring is a cap *n*, each of the side walls of which is provided with a recess *o* for the pin *p* of the pulley *q*. The point where the two 70 ends of the wire meet can also be placed at some other point.

The form of construction shown in Fig. 5 differs from the form of construction shown in Fig. 4 only in so far as the cap *n* is open 75 at the upper end and that the ends *m'* of the wire are placed alongside one another in order thus to secure the cap in its position.

The form of construction shown in Fig. 6 also possesses a cap which is open at its upper 80 end. In order to hold the cap, the ends of the wire *m''* are bent slightly outwards.

In the case of any of the forms of construction shown, the hook can be replaced by an 85 eyelet.

I claim:

1. In a holder with pulley for drawing curtains, a cap, said cap enclosing the upper half of said pulley and being provided with recesses serving as supporting bearings for 90 said holders on the axle of the pulley.

2. In a holder with pulley for drawing curtains, a cap, said cap enclosing the upper half of said pulley and being provided with notches of angular shape serving as supporting 95 bearings for said holes on the axle of the pulley.

3. In a holder with pulley for drawing curtains, said holder consisting of a wire of which one end forms a hook, the other end 100

forming a ring surrounding said pulley, a cap, said cap being supported by said ring and enclosing the upper half of said pulley and being provided with recesses serving as bearings for the axle of the pulley.

4. In a holder with pulley for drawing curtains, said holder consisting of a wire of which one end forms a hook, the other end forming a ring surrounding said pulley, a cap, said cap being supported by said ring and enclosing the upper half of said pulley and being provided with notches serving as bearing for the axle of the pulley, said cap being open at its upper end, the ends of the wire of said ring being partly bent over to secure the cap in position.

5. In a device of the class described, a supporting member, a roller disposed in said supporting member, said roller being provided with lateral trunnions, and a cap member operatively connected with said supporting member and enclosing the upper portion of said roller, said cap member having bearings in the lower extremity thereof embracing said trunnions and constituting supporting means for said cap and supporting member.

6. In a device of the class described, a supporting member, a roller disposed in said supporting member, said roller being provided with lateral trunnions, and a cap member operatively connected with said supporting member and enclosing the upper portion of said roller, said cap member having bearing notches in the lower edge thereof embracing said trunnions, and resting solely on said trunnions.

7. In a device of the class described, a supporting member formed of a single length of wire rebent on itself and having a portion of the wire at the free extremities of the same spaced apart forming a roller-receiving portion, a roller in said roller receiving portion, said roller having lateral trunnions, and a cap member disposed over the upper half of said roller and having an opening therein with which the extremities of said wire are adapted to be interlocked, said cap member having recesses therein in which the roller trunnions are seated to sustain the weight on said supporting member.

In testimony whereof I have affixed my signature.

AUGUST RAPP.
